UNITED STATES PATENT OFFICE.

HUBERT EDWARD SHEWARD, OF MIDDLESEX, ENGLAND.

DESIGN FOR A LAMP-BRACKET.

48,132.

Specification for Design.

Patented Nov. 9, 1915.

Application filed October 3, 1914. Serial No. 864,956. Term of patent 7 years.

To all whom it may concern:

Be it known that I, HUBERT EDWARD SHEWARD, a subject of the King of Great Britain, residing in Middlesex, England, have invented a new, original, and ornamental Design for a Lamp-Bracket, of which the following is a specification, reference being made to the accompanying drawing, forming part thereof.

In the drawing: Figure 1 is a side eleva-

tion of the lamp bracket showing my new design; Fig. 2 is a front elevation; and Fig. 3 is a plan of the bracket.

I claim.

The ornamental design for a lamp bracket as shown.

HUBERT EDWARD SHEWARD.
